UNITED STATES PATENT OFFICE.

GROVER C. KELLY, OF BUFFALO, NEW YORK.

KNOCKDOWN TABLE AND THE LIKE.

1,269,193.

Specification of Letters Patent. Patented June 11, 1918.

Application filed April 24, 1916. Serial No. 93,243.

To all whom it may concern:

Be it known that I, GROVER C. KELLY, a citizen of the United States, residing at Buffalo, in the county of Erie and State of New

5 York, have invented certain new and useful Improvements in Knockdown Tables and the like, of which the following is a specification.

My invention relates to articles of furniture of the "knock-down" type, and more particularly to a table, for occasional use adapted to have its component parts disassembled for conveniently storing the same.

Tables of this type are used occasionally 15 in clubs and in hotels and other public places, for banquets and the like, and are invariably stored within a compact space when not in use. It is often found necessary to quickly remove the tables after a 20 banquet so that the space occupied by them may be cleared and used for other purposes.

It is the purpose of my invention to provide a table of this character, the component parts of which can be quickly assembled 25 and disassembled, and which when assembled, will be capable of sustaining considerable weight and will also rigidly support the table top and furnish a solid structure.

It also has for its object to provide a table 30 of this type which is simple in construction, inexpensive and durable, and the component parts of which can be assembled with ease and speed and which can be readily disassembled.

35 It has for a further object to provide a table which may be constructed of light material so as to reduce the weight to the minimum, thus enabling the same to be conveniently transported or moved about from one 40 place to another.

With these and other objects in view, the invention consists in the novel features of construction and in the arrangement and combination of parts to be hereinafter described and particularly pointed out in the subjoined claims.

In the drawings,—

Figure 1 is a side elevation of a table constructed according to my invention. 50 Fig. 2 is a horizontal section taken on line 2—2, Fig. 1, looking up.

Fig. 3 is a transverse section through a portion of the table taken on line 3—3, Fig. 1, the lower portion of the leg being shown 55 in elevation.

Fig. 4 is an enlarged fragmentary section taken on line 4—4, Fig. 3.

Fig. 5 is an enlarged fragmentary section taken on line 5—5, Fig. 1.

Fig. 6 is a detached perspective view of 60 one of the swinging leg braces or brace members.

Fig. 7 is an enlarged section taken on line 7—7, Fig. 3, with the brace member in dotted lines in said last-mentioned figure illustrated in full lines.

Fig. 8 is a side elevation of a table provided with a pair of intermediate legs.

Reference being had to the drawings in detail, 10 designates the table top which is 70 shown of rectangular formation, but may be round or otherwise formed. Arranged lengthwise on the underside of said top are two metallic stiffening bars 11, 12, each bar having at opposite ends hollow enlargements 75 or sockets 13 and each enlargement or socket has a lateral projection 14 extending toward the transverse center of the table top and spaced from the underside of the bar by a notch 15. The bars 11, 12 are screwed or 80 otherwise fastened to the underside of the table top and serve to prevent warping of the top. By arranging the bars lengthwise on the underside of the top, the latter may be made comparatively thin so that a table 85 of light weight results from such construction.

At suitable distances from the enlargements or sockets 13 I apply to the underside of the bars 11, 12, latch-receiving socket-members 16, but if desired, these members may be formed integrally with said bars or secured directly to the underside of the table 90 top.

The parts thus far described constitute 95 the table top or one of the component parts of the table. In a table of ordinary length, two pairs of legs will be found sufficient to properly support the top and any weight it may have to carry, but a table of 100 considerable length may require one or more intermediate pairs of legs, as shown in Fig. 8; but in either case the end pairs of legs are similarly constructed. Each end pair of legs forms one of the component parts of 105 the table and comprises two connected leg members 17 which are preferably reduced in thickness at their upper ends, as at 18, to provide a shoulder 19. These legs may be of any cross sectional formation and of 110

any contour, and while the upper reduced ends are designed to have parts swing thereon and are therefore preferably cylindrical, it is not necessary that they be cylindrical throughout their lengths, although so shown.

10 The leg members of each end pair are connected together by a connecting or tie member 20, preferably in the form shown, but any other form of connecting member may be used so long as it is capable of rigidly connecting and maintaining the legs of each pair in connected condition.

15 Mounted for horizontal swinging movement on the reduced upper end of each of said legs is a brace member 21. Each brace member comprises converging arms 22, 23, one of which is substantially horizontal and the other inclined to meet the outer end of 20 the horizontal arm, at which end the brace member has an enlargement or head 24. The inner ends of the arms 22, 23 are provided with alined hubs 25 having openings 26 therethrough. Through the openings of 25 the alined hubs of each brace member the upper reduced end of a leg member 17 is passed and when inserting a leg member through said hubs, a spacing sleeve 27 is placed upon the leg member so as to fit 30 between said hubs, said spacing sleeve 27 being pinned to the leg member, as at 29. Each of the leg members extends upwardly beyond the upper surface of the upper hub 25, as clearly shown in Fig. 4.

35 The projecting upper ends of the leg members of each pair of legs are inserted within the sockets 13 of the metallic bars 11, 12 at the same end of the table, and when thus arranged the brace members are 40 free to swing on the table legs. The upper or horizontal arms 22 of the brace members are provided with upward and inward projections 30 forming substantially locking hooks which are adapted to swing into the 45 notches 15 of the sockets 13 when said members are swung parallel with the side edges of the table top. When the parts of the table are disassembled, the brace members of each pair of legs are swung transversely, 50 as shown by dotted lines in Fig. 3, and are thus situated between the legs. When thus positioned the locking hooks of said members are disengaged from the notches in the sockets 13 so that the connected legs are free 55 to be withdrawn from said sockets. When the brace members are swung into bracing position; *i. e.* when they are positioned parallel with the side edges of the table top, or substantially so, they are preferably 60 locked at their outer ends to the table top, and for this purpose a spring latch 31 is arranged slidably within each of the heads 24 at said outer ends. Each enlargement or head therefore has a socket 32 formed 65 therein and a small bore 33 extending from

said socket downwardly to the bottom face of the enlargement.

Each latch 31 comprises a sliding bolt 36 fitting in the socket 32, a rod 37 formed on said bolt and fitting in the bore 33, and a 70 coil spring 38 surrounding the rod and bearing at one end against said bolt and at its other end against the bottom wall of the socket, thus serving to hold the engaging end of said bolt projected from the upper 75 face of said enlargement or head. To the projecting end of said rod a head 42 is threaded or otherwise secured so as to permit of conveniently manipulating the latch.

80 The enlargement or head 24 at the outer end of each brace member has a dove-tailed portion 44 projecting from its upper face which is adapted to enter a correspondingly formed groove in the coöperating latch-receiving socket member, thus when the brace 85 members are swung into bracing position, the dove-tailed projection of each enters the correspondingly formed groove of its coöperating socket member and prevents flexing of the table top in a vertical direction. 90 The table top is thus effectually locked and the legs properly braced to sustain any weight which may be placed upon the table.

95 The connecting members 20 are arch-shaped, as shown in Fig. 3, thus giving space 100 for the legs of a person sitting at the end of a table. In cross section each of these connecting members is of angle formation, except midlength where a flange 45 is formed along the inner edge of the member, the latter being adapted to be engaged by the sliding bolts 36 of the braces when they are swung transversely for the purpose of 105 storing the component parts of the table, the mere swinging of the braces causing the 110 curved faces at the outer ends of the bolts to engage the flanges 45, and by the latter be caused to retract against the action of the springs 38, which springs immediately 115 force the latch bolts outwardly after they have passed the inner faces of said flanges, as clearly shown in Fig. 7.

120 When an intermediate pair of legs are used, the brace members are extended in opposite directions from the supporting legs to which they are attached, as shown in Fig. 8, thus the hub portion is situated between the enlargements or heads at the outer ends of the brace members; the brace members being otherwise constructed similar to those applied to the end pairs of legs. However, if desired, a pair of brace members adapted to swing in opposite directions may be applied to the reduced upper end of each supporting leg.

125 Having thus described my invention, what I claim is—

1. An article of furniture comprising a top member having sockets, two pairs of connected legs, a swinging brace member 130

applied to each leg, a dove-tailed connection between said top member and the free or outer end of said brace member, and means for detachably fitting the upper ends 5 of said legs into said sockets.

2. An article of furniture comprising a top member having two pairs of sockets, two pairs of connected legs having their upper ends fitted into said sockets, a swinging 10 brace member applied to each leg, co-acting locking elements on said brace members and sockets, and means for detachably connecting the outer ends of said brace members with said top member at points distant from 15 said sockets.

3. A knock-down table comprising a table top having sockets provided with horizontal notches, table legs having their upper ends slidably retained in said sockets, and swinging 20 elements on said table legs having hook-shaped portions adapted to enter the notches of said sockets.

4. A knock-down table comprising a table top having a plurality of sockets, 25 each socket having a lateral projection and a horizontal notch between said lateral projection and said table top, a leg having its upper end inserted into each of said sockets, and a brace member arranged 30 on each leg and having its axis coincident with the axis of its co-operating leg so as to swing thereon and also having a horizontally disposed hook-shaped portion adapted to enter the notch of the co-operating 35 socket, each brace member having a spring latch at its outer end adapted for connection with the table top.

5. A knock-down table comprising a table top having sockets, each socket being provided with a notch, a pair of connected legs 40 at each end of the table having their upper portions detachably fitted into said sockets, a swinging brace member on each leg beneath its socket having a projecting portion 45 engaging the notch of said socket and having also an enlargement at its outer end provided with a spring latch, and socket members on the underside of said table top adapted to receive said spring latches.

6. A knock-down table comprising a table top having a pair of spaced parallel reinforcing bars secured to the underside thereof, each bar having a socket at each end, a pair of connected legs at each end of 55 the table detachably fitted into the sockets at said end; a brace member held on each leg to swing thereon and comprising outwardly converging arms provided with an enlarge-

ment at their outer ends, the upper arm of each brace member having means interlocking with its co-operating socket, a spring latch in each of said enlargements, and socket members on the underside of said table top adapted to be engaged by said spring latch. 60 65

7. A knock-down table comprising a table top having spaced reinforcing bars secured to its underside provided with sockets at opposite ends, each socket having a notch formed therein, a pair of connected supporting legs at opposite ends of the table top having their upper ends detachably fitted into said sockets, brace members arranged to swing on said supporting legs so as to assume positions between the legs of each 70 pair or positions parallel with the sides of the table, each brace having a projecting portion adapted to fit into the notch of the co-operating socket when swung into the last-mentioned position and having also a dove-tailed projection at its outer end, socket members secured to the underside of the table top having dove-tailed grooves to receive said dove-tailed projections, and a spring latch in each of said heads adapted to 80 85 latch into said socket members.

8. A knock-down table comprising a table top having notched sockets, a leg adapted to detachably fit into each socket, socket members secured to the underside of said 90 table top, each having a dove-tailed groove, and swinging braces on said legs, each brace comprising converging arms having hub portions fitting onto its co-operating leg, an upwardly and inwardly extending portion 95 adapted to enter the notch of the co-operating socket, and an enlargement at the outer ends of said arms having dove-tailed projections adapted to fit the dove-tailed groove of its co-operating socket member and a 100 spring latch within each enlargement or head adapted to engage said socket members.

9. A knock-down table comprising a table top, two pairs of connected legs connected to 105 said table top and a swinging element on each of said table legs, each swinging element having its axis coincident with the axis of the leg on which it swings and being adapted to lock and brace the table top to 110 said leg and to be locked in position between a pair of connected legs when disconnecting the legs from the table top.

In testimony whereof I affix my signature.

GROVER C. KELLY.
